UNITED STATES PATENT OFFICE.

WILKIN L. SULLIVAN, OF JACKSON, MISSISSIPPI.

HAY-PRESS.

1,105,007.

Specification of Letters Patent.

Patented July 28, 1914.

Application filed March 13, 1913. Serial No. 754,152.

To all whom it may concern:

Be it known that I, WILKIN LEONARD SULLIVAN, a citizen of the United States, residing at Jackson, in the county of Hinds 5 and State of Mississippi, have invented a new and useful Hay-Press, of which the following is a specification.

This invention relates to hay presses and particularly to a press in which rotary motion of the power applying mechanism effects the reciprocation of the presser head which is adapted to reciprocate in a casing to which material to be baled or pressed is delivered in any convenient manner.

15 An object of this invention is to provide a novel frame for supporting the operating mechanism, the said frame being associated with a guide or track adapted to support the power applying mechanism while the same is traveling with relation to the frame; furthermore, an object of this invention is to provide novel means for moving a pitman which is connected to the presser head through the medium of a bar, in one direction, and means for moving the pitman in the opposite direction so that the presser head is reciprocated.

20 A further object of this invention is to provide novel means operated by the reciprocation of the bar heretofore mentioned for delivering the material to the casing or hopper in which the presser head operates.

With the foregoing and other objects in view, the invention consists in the details 35 of construction, and in the arrangement and combination of parts to be hereinafter more fully set forth and claimed.

In describing the invention in detail, reference will be had to the accompanying 40 drawings forming part of this specification wherein like characters denote corresponding parts, in the several views, and in which—

Figure 1 illustrates a perspective view of 45 a hay press embodying the invention; Fig. 2 illustrates an enlarged detail view showing a plan of the actuating mechanism for the presser head; Fig. 3 illustrates a plan view of the hopper and parts associated therewith; Fig. 4 illustrates a side elevation of the 50 said hopper; and Fig. 5 illustrates a perspective view of the presser head and a fragment of the rod connected thereto.

In these drawings 1, 1, denote rods which, 55 at the ends remote from the frame, are adapted to be connected together or con-

nected to a suitable means for the attachment of power applying mechanism or devices, it being the intention of the inventor to preferably provide the same with means 60 for hitching draft animals thereto so that the outer ends of the rods will be pulled to operate the mechanism to which the inner ends of the rods are connected.

The hay press consists in a frame-like 65 structure which may be regarded as the stationary portion of the mechanism, the said frame consisting of the parallel frame members 2 and 3, and 4 and 5, the former members 2 and 3 being straight and extending to 70 the hopper (to be hereinafter described), the said members 2 and 3 being then extended at an angle to the straight portion and further bent at an angle so that the ends remote from the hopper extend across the 75 outer ends of the members 4 and 5, and terminate in supports for the circular track 6, the said circular track being supported furthermore by the portions of the frame formed by the outer ends of the said members 80 4 and 5. A web or brace 7 is placed at the intersection of the members 2 and 3 and 4 and 5 and the said members are connected or attached to the brace to strengthen the structure and form a support for a king pin 85 8 on which the arm 9 is mounted, the said arm 9 being adapted to rotate on the king pin under the influence of the rods 1 which have their inner ends connected to said arm. The members 2 and 3 are held in spaced relation to each other by bolts 10 which bolts 90 contain the spacing collars 11 between the members 2 and 3 so that the said members 95 are held apart. The members 4 and 5 are likewise held apart by bolts 10 and collars 11, such as are employed in holding the members 2 and 3 in spaced relation to each other.

A link 12 has one end mounted on a pivot 13 in the web and the outer end of the link 100 is pivotally connected to a pitman 14 by the pivot 15, and the end of the pitman remote from the pivot 15 is connected to a sliding member or bar 16, which bar has its outer end connected to a presser head 17. There 105 is mounted on the pivot 15 a ratchet wheel 18 which is normally held against rotation by the dog 19 which dog is mounted on a pivot 20 and has its nose pressed normally into engagement with the ratchet wheel by 110 a spring 21. The end of the dog remote from the nose is curved to form a tail piece 22

adapted to be forced into engagement with a portion of the frame so that the nose of the dog will be forced out of engagement with the ratchet wheel to permit rotation of 5 the ratchet wheel for a purpose to be presently explained.

A lever 23 is connected to the frame by a pivot 24 on which it oscillates, the said lever having one end connected to the pitman 14 10 by the link 25 which link has one end pivoted to the lever 23 and the opposite end pivoted to the pitman 14 by the pin 26. The end of the lever remote from the pitman terminates in a hook 27 which has substantially 15 the functions of a cam operated on by the actuating mechanism for oscillating or moving the lever in one direction and thereafter communicate motion in one direction to the pitman. As stated, the pitman is 20 operated in one direction by power applied to the lever, whereas the said lever is actuated in the opposite direction by power applied to the ratchet wheel, the power being applied in both instances through the instrumentality of the arm 9.

A brace 28 has one of its ends connected to an end of the arm 9 and the said brace crosses one of the rods 1 and is attached to the other rod 1 by the clip 29, which clip also serves 30 to retain the brace 30 extending between the two rods 1, 1. The brace 28 and the brace 30, it will be seen, serve to produce a rigid structure and a clip 31 serves to connect the brace 28 to one of the rods 1 at their intersection. The clip 31 further serves as a 35 means for anchoring one end of a stirrup 32, which stirrup has its opposite end attached to the arm 9 by the fastening 33. The stirrup 32 has ears 34 forming supports for 40 a pin 35 on which an anti-friction roller 36 is mounted, the said anti-friction roller being adapted to travel on the track 6 as the arm 9 is rotated. The arm 9 comprises two parallel strips held in spaced relation by 45 bolts 37 and collars 38, one of which is at each end of the arm. The function of these bolts and collars is to engage the ratchet wheel and the hook 27 of the lever 23 alternately so that they will actuate the pitman. 50 The sections 2 and 3 and 4 and 5 of the frame are provided with suitable braces such as 39, 40, 41, etc., arranged in pairs on the upper and lower surfaces of the frame.

From an inspection of the drawing, it will 55 be observed that when rotary motion is communicated to the arm 9, the anti-friction roller 36 will travel around on the track 6 and the ends of the arm will alternately operate the pitman. In Figs. 1 and 2, the 60 end of the arm is shown as being released from the ratchet to engage the hook 27 of the lever. A continuation of the rotation of the arm from the position shown in these figures will result in forcing the hook 27 to 65 the dotted line position of said hook, shown

in Fig. 2 and owing to the fact that the lever is mounted on the pivot 24 of the fixed frame, the pitman will be forced to the dotted line position shown in Fig. 2. Further movement of the arm will result in the 70 opposite end coming in contact with the ratchet wheel and as the said ratchet wheel is held against rotation by the dog, power applied to the arm will result in forcing the pitman inwardly and downwardly to the full 75 line position of said lever as shown in Fig. 2. During the travel of the pitman to the last mentioned position, the tail 22 of the dog abuts a stationary portion of the frame and the nose of the dog is forced out of engagement 80 with the ratchet so that the said ratchet is free to again rotate, releasing the end of the arm therefrom and permitting it to travel in engagement with the hook 27 for a repetition of the operation. It is obvious 85 therefore that, upon rotation of the arm, the pitman is reciprocated and as the end of said pitman is connected to the sliding bar 16, the presser head will be operated.

The hopper 42 which may be otherwise 90 known as a feed box or receptacle into which the material is delivered for packing and which will be hereinafter referred to as a hopper, comprises a rectangular metal frame having an open end into which the material 95 is delivered. The forward end of the hopper has standards 43 on which the arms 44 of a packer are pivoted, the said packer comprising a frame-like structure connected to the arms 44, which frame-like structure 100 contains the fingers 45 which are adapted to engage and force material into the hopper. The arms 44 have a brace or curved base 46 to which a connecting rod 47 is pivoted, said connecting rod having a joint 48 and 105 the end of the connecting rod remote from the packer is pivoted on the ears 49 carried by the reciprocating rod. Thus, as the reciprocating rod is moved, the packer is moved from the full line position shown in Fig. 4 110 to the dotted line position of said packer, and material is delivered to the hopper.

Steel wire dogs 50, approximately triangular in shape, each has an end anchored in the side of the hopper as at 51 and the opposite end extends through the hopper and is actuated by a coiled spring 52. These springs present shoulders which are adapted to retain the material that has been forced past them, preventing the expansion of said 115 material, after it has been compressed.

I claim

1. In a hay press, a hopper, a plunger 120 slidable therein, a rod connected to the plunger, a pitman pivotally connected to the rod, a link pivotally connected to the pitman, a frame, means for pivotally connecting the ends of the link remote from the pitman to the said frame, a ratchet wheel rotatably mounted at the junction of the link and pit- 125

man, a dog for retaining the ratchet wheel in different positions of adjustment, an arm, a pin carried by the frame and on which the arm is rotatably mounted, means for rotating the arm; the said ratchet wheel being in the path of travel of the arm, whereby the said pitman is moved in one direction by the arm, a lever pivotally connected to the frame, means for connecting one end of the lever to the pitman, said lever having a hooked end adapted to be engaged by the arm and moved thereby for operating the pitman in an opposite direction to that in which it is moved by the arm when engaging the ratchet wheel.

2. In a hay press, a frame, a reciprocating member, a head connected to the said reciprocating member for pressing material, a pitman connected to the reciprocating member, a link pivoted to the frame and to the pitman, a ratchet wheel rotatably mounted at the junction of the pitman and link, a dog adapted to retain the ratchet wheel stationary, said dog being moved to release the ratchet wheel upon contact with a stationary portion of the frame, an arm, means for rotatably mounting the arm on the frame, whereby the ratchet wheel will be in the path of its travel for communicating motion to the pitman, a lever pivoted to the frame, means for connecting the lever to the pitman, a hook on the end of the lever adapted for intermittent engagement of the arm, whereby movement of the arm is communicated to the pitman and means for rotating the arm.

3. In a hay press, a frame, a reciprocating member, a presser head carried thereby, a member with which the presser head connects for packing material, a pitman connected to the reciprocating member, a link pivoted to the frame and to the pitman, an arm, means for pivotally mounting the arm on the frame, a track for supporting the arm in its travel, anti-friction means interposed between the arm and track, means for moving the arm around the track, a ratchet wheel at the junction of the link, and pitman in the path of travel of the arm, whereby movement is communicated to the pitman by the arm, a lever, means for pivotally mounting the lever on the frame, means for connecting one end of the lever to the pitman, and means on the lever adapted to be

engaged by the arm for swinging the lever and operating the pitman upon a release of the arm from the ratchet wheel.

4. In a hay press, a frame, a reciprocating member, a presser head carried thereby, a member with which the presser head connects for packing material, a pitman connected to the reciprocating member, a link pivoted to the frame and to the pitman, an arm, means for pivotally mounting the arm on the frame, a track for supporting the arm in its travel, anti-friction means interposed between the arm and the track, means for moving the arm around the track, a ratchet wheel at the junction of the link and pitman in the path of travel of the arm, whereby movement is communicated to the pitman by the arm, means for effecting the release of the arm from the ratchet wheel, a lever, means for pivotally mounting the lever on the frame, means for connecting one end of the lever to the pitman, means on the lever adapted to be engaged by the arm for swinging the lever and operating the pitman upon a release of the arm from the ratchet wheel.

5. In a hay press, a frame, a reciprocating member therein, a presser head carried by the reciprocating member, a member with which the reciprocating member connects, means for delivering material to the member, a connection between the reciprocating member and the feeding member, a pitman connected to the reciprocating member, a link pivoted to the pitman and to the frame, a ratchet wheel at the junction of the link and pitman, a dog for holding the ratchet wheel in different positions of adjustment, said dog being released from the ratchet wheel by engaging the portion of the frame, an arm, means for pivotally connecting the arm to the frame, a track, means connected to the arm and engaging the track for guiding the said arm, means for operating the arm, a lever having a hook on its end, means for pivotally connecting the lever to the frame, means for connecting the end of the lever to the pitman, the said hook being engaged by the arm for operating the lever when the arm is released by the ratchet wheel.
